FLATIRON STAND

George R. Harris, Montrose, Calif., assignor, by
mesne assignments, to Zeigler-Harris & Co.,
Inc., a corporation of California

Application February 2, 1946, Serial No. 645,042

5 Claims. (Cl. 248—117.3)

1

This invention relates to flat irons and has particular reference to improvements in stands on which to support such irons while in use.

Electrically heated irons are in general use in modern homes and they are fitted to receive the end of a light cord extended from a wall socket. This cord usually overhangs the ironing board, when the iron is on its stand thereon, in such a manner that the person doing the ironing, or any person passing by the ironing board, is liable to come in contact therewith and accidentally give it a jerk sufficiently strong to cause the iron to topple over and to land on the ironing board or on the floor.

A still greater danger is that curiosity, or the desire to play, will cause children to take hold of the cord and, if the ironer should happen at the moment to be absent from the board, to pull the iron off the stand and board, and serious burns often result from such accidents.

In view of the foregoing, it is the object of the present invention to provide an improved flat iron stand. More particularly, it is my object to provide a stand which, when the iron is set thereon, forms a casing completely enveloping the body portion of the iron.

A further object is to provide such a casing, out of which the iron may be lifted and into which it may again be seated as easily and conveniently as the iron is placed on any conventional stand.

Another object is to provide an iron encompassing stand from which the iron will not become separated in case the stand should topple over and even when it is dragged along the ironing board or the floor by accidental pulls on the cord thereof.

Finally it is the object of my invention to embody into such protective casing a heat-insulating lining to the end that the heat radiating from the iron may not penetrate to the outer surface of the casing.

With these and other objects in view, the invention resides in the combinations hereinafter described in detail, and drawings are hereto appended, in which a preferred form of the invention is illustrated.

In the drawings:

Fig. 1 is a plan view of a device embodying the invention as it appears when closed;

Fig. 2 is a side elevational view showing a slightly modified form of the invention, in open position;

Fig. 3 is an end view of the device with the near end of the casing thereof broken away for

2

the sake of clearness and showing a flat iron in position therein; and

Fig. 4 illustrates the position taken by the device when accidentally toppled over.

As indicated in the drawings, the device is made in two parts 1 and 2, connected together by hinges 3. The part 1 is shown mounted on legs 4 of sufficient height to maintain the device high enough above the supporting surface to permit the part 2 to swing into the open position indicated in dotted outline in Fig. 3 and in full outline in Fig. 2, when the iron is removed from the device. It is furthermore to be noted that a plate 5 is secured to the part 2 to rest on the inner surface of the part 1 when the casing is closed, as indicated in Figs. 1 and 3, but to rise into the dotted line position of Fig. 3 when the part 2 is swung open. In Fig. 2 this plate, 6, is shown shaped somewhat differently, merely to indicate that the particular width of this part is immaterial; it may be made as wide as desired.

When the casing is standing on its legs, and before the iron is placed therein, the part 2 takes the open position indicated in Figs. 2 and 3. Actually it would take the same position in Fig. 1, and it is in that view shown closed merely in order better to indicate the general outline of part 2.

The iron is placed within the casing by moving it from the left side against the elevated plate 5, thereby to cause this plate to swing into the full line position 5 and the part 2 to swing upward into closed position. When it is desired again to remove the iron, it is merely required to lift it out of the casing and the part 2 is by gravity again swung open.

It is important to note that this seating and removing operation is no more difficult than the placing of the iron on an ordinary support.

But it is more important to observe that the iron can only be removed from the casing by lifting it straight out thereof and that it is, by the plate 5 shown in Fig. 1 or plate 6 of Fig. 2, locked in position therein if it is attempted to pull it out of the casing sidewise or when the device is toppled over to one side, as indicated in Fig. 4, or to the other. It may be dragged along the floor by its cord, but it cannot become detached therefrom until returned to upright position. And, as the casing is heat insulated, it may be picked by hand and set on its legs without danger of injury to the person handling it.

The insulating is conveniently effected by placing a lining of sheet asbestos 7, 8, or the like, within the casing, whereupon an inner metal

lining 9, 10 may be added, if desired, although, when the plate 5 is made substantially the full length of the open space within the casing, such inner lining may not be found necessary. Other modifications may be embodied within the scope of the claims hereto appended, with a view to provide the simple, convenient and safe flat iron support of the invention. It may, for example, be found advantageous to provide vents in the bottom of the casing, as indicated at 12, in Fig. 1.

I claim:

1. A flat iron stand comprising, a casing shaped to encompass the bottom and sides of a flat iron, said casing being made in two parts hinged together lengthwise of the base thereof, legs maintaining one of said parts elevated above a support, the other part normally by its own weight maintained downwardly and outwardly swung open, and a plate rigidly secured to said normally open part and substantially vertically projecting therefrom, said plate being contacted by the iron when the latter is placed in position within the casing to come to rest against the base surface of the first named part when the casing is closed about the iron.

2. A flat iron stand comprising, a casing shaped to encompass the bottom and sides of a flat iron, said casing being divided lengthwise of the base thereof into a wider portion mounted on legs, the narrower portion of the casing being hingedly connected to the wider portion thereof and by its own weight free to swing outwardly and downwardly from the wider portion, a plate extending from the narrow portion of the casing to swing therewith on the casing hinge and to come to rest against the base surface of the wide portion when the casing is closed about the iron, the latter being seatable in the casing by contact with said plate and by moving the plate into contact with the base surface of the wider casing portion.

3. A flat iron stand comprising, a sheet metal casing shaped to encompass the bottom and sides of a flat iron, the upper edge of the casing being inwardly curled, the casing being divided lengthwise of the base thereof into a wider portion mounted on legs, the narrower portion of the casing being hingedly connected to the wider portion thereof and by its own weight free to swing outwardly and downwardly from the wider portion, a plate extending from the narrow portion of the casing to swing therewith on the casing hinge and to come to rest against the base surface of the wide portion when the casing is closed about the iron, the latter being seatable in the casing by contact with said plate and by

moving the plate into contact with the base surface of the wider casing portion, and heat insulating lining within the casing, the upper edge of said lining being held locked within the curled edge of the casing.

4. A flat iron stand comprising, a casing shaped to encompass the bottom and sides of a flat iron, the upper edge of the casing being inwardly curled, the casing being divided lengthwise of the base thereof on a straight line beginning at the pointed front end of the casing and continuing closer to one side edge thereof into a wider portion mounted on legs and a narrower portion, the narrower portion of the casing being hingedly connected to the wider portion thereof and by its own weight free to swing outwardly and downwardly from the wider portion, a plate extending from the narrow portion of the casing to swing therewith on the casing hinge and to come to rest against the base surface of the wider portion when the casing is closed about the iron, the latter being seatable in the casing by contact with said plate and by moving the plate into contact with the base surface of the wider casing portion, the upper edge of said lining being held locked within the curled edge of the casing.

5. A stand for a pointed flat iron comprising, a sheet metal casing shaped to encompass the base and slanting sides of the iron, said casing being divided into a wider and a narrower part on a straight line extending from the pointed front end thereof to the rear end thereof nearer one side edge thereof, hinges interconnecting the two parts, a plate rising from inner edge of the narrow part of the casing to swing with that narrower part on said hinges until it comes to rest on the base surface of the wider part when the casing is closed, the narrow casing part being free to swing outward and downward on the hinges to open the casing to provide space for seating of an iron, heat insulating lining within the casing, and vents for carrying heat from the iron through said lining and the outer shell of the casing.
